UNITED STATES PATENT OFFICE.

GEORGE S. CRAMPTON, OF PHILADELPHIA, PENNSYLVANIA.

TRIAL-LENS MOUNTING FOR OCULISTS AND OPTICIANS.

Application filed June 3, 1922. Serial No. 565,616.

Objects of the present invention are, first, to provide for accurately reading the scale which indicates the position of the axis of the cylindrical lens; second, to accomplish this object and at the same time provide for a broad surrounding ring to take hold of without danger of smearing the lens; third, to arrange the scale and axis markings at a considerable distance from the center of the lens; and fourth, to provide an improved metal mounting or cell for a cylindrical trial lens which obviates defects and difficulties heretofore encountered and insures facility and accuracy in use.

15 The invention will be claimed at the end hereof but will be first described in connection with the embodiment of it chosen from other embodiments for the sake of illustration in the accompanying drawing forming 20 part hereof and in which—

Figure 1 is a front view, drawn to an enlarged scale, showing parts of a trial frame and a cylindrical trial lens mounting or cell embodying features of the invention.

25 Fig. 2 is a transverse sectional view of the same.

Fig. 3 is a rear view of the cell or mounting, and

30 Fig. 4 is a sectional view drawn to a still larger scale of parts of the cell or mounting and of the driving wheel.

Referring to the drawings the metallic mounting or cell for a cylindrical trial lens 1 comprises a centrally perforated metal 35 disk 2 having on one face a laterally projecting annular hub 3 provided with axis marking 4 and having on the rim of the hub a marginal projecting flange 5. The bore of the disk is provided with a lens-bezel 6, Fig. 4, and the rim of the disk is shown as double sloped as at 7. The face of the disk opposite the hub 3 is countersunk as at 8 and may be circularly or otherwise chased as at 9. 10 is a graduated arc plate, 40 which is generally U-shaped, and 11 is a driving wheel of a trial frame, and the arc plate and the driving wheel are usual provisions of a trial frame which is too well understood to require detail illustration or 45 description.

50 However, in the present case the rim of the wheel 11 is grooved for cooperation with the sloping rim 7 of the disk. The groove in the wheel is shown as V-shaped in cross-section and the rim of the disc 2 is shown as of the form of a truncated pyramid in radial section.

In use the band of metal provided around the lens is wide enough to afford a good finger grip for placing the lens mounting or cell in and removing it from the trial frame. 60 The countersunk face affords a good finger hold which by chasing is improved. The hub, or, more accurately, the periphery of the hub is of comparatively large diameter so that the markings on the arc plate 65 10 need not be fine or close together. The hub lies flush with the surface of the arc plate, see Fig. 2, so that the axis marking 4 and the graduations on the arc plate come in close proximity and alignment and therefore 70 can be accurately and easily read, parallax being entirely avoided. The tongue-and-groove provisions between the rims of the wheel 11 and cell or mounting 2 insure accurate turning of the cell or mounting 75 without danger of relative slipping. The flat part of the lens may well be mounted toward the front of the mounting or cell.

It may be said that the rim of the hub confronts the rim of the arc plate, and the 80 flange 5 and back of the arc plate abut flatwise and the thickness of the lens may project backward leaving a flat face of the lens at the front, or either or both surfaces of the lens may be curved as desired.

85 In the use of the word metal in connection with the lens holding rim I do not intend to imply that the rim is necessarily of metal because other suitable material, as celluloid, might be substituted for metal 90 and of course a lens-bezel is an example of means for securing the lens in the rim.

95 It will be obvious to those skilled in the art to which the invention relates that modifications may be made in details of construction and arrangement without departing from the spirit of the invention which is not limited as to those matters or otherwise than as the prior art and the appended 100 claims may require.

I claim:

1. A mounting or cell for a cylindrical trial lens comprising a centrally apertured disk having on one face a laterally projecting annular hub provided with axis marking and having on the rim of the hub a marginal projecting flange providing a finger grip.

105 2. A mounting for a trial cylindrical lens comprising a centrally apertured disk provided on the surface of its bore with a lens-bezel and at its rim with a double slope and

having at one face an annular hub present- its front face with graduations, and a lens 20
ing a flat surface for axis marking and hav- mounting or cell comprising a centrally
ing its other face countersunk. apertured disk having on one of its faces a

3. A mounting for a cylindrical trial lens laterally projecting annular hub provided
5 comprising a metal disk having a central with axis marking and arranged substantial-
opening in which the lens is mounted and ly flush with the front face of the plate 25
a double beveled periphery any radial sec- and having on the rim of the hub a marginal
tion of which is a truncated pyramid, the projecting circular flange abutting flatwise
10 apex of which is at a definite distance from on the rear face of the plate.

10. In a trial frame the combination of a 6. In a trial frame the combination of a
4. In a trial frame the combination of a lens holder including a driving wheel and 30
graduated arc plate and a trial cylinder lens a graduated generally U-shaped arc plate,
mounting or cell comprising a centrally per- and a centrally perforated disk having rim
15 forable in the frame and hav- contact with the wheel and provided on one
ing on one face a projecting annular hub face with a cylindrical hub flush with the
substantially flush with the surface of the arc arc plate and having axis markings, there 35
plate and having an axis marking. being tongue-and-groove provisions between

5. In a trial frame the combination of a the rims of the disk and wheel.
generally U-shaped arc plate provided on
